ELECTRODE WHEEL HOLDER

Julius V. Bergfeldt, New Britain, Conn.

Application January 11, 1957, Serial No. 44,484

Term of patent 14 years

(Cl. D26—1)

FIG. 1

FIG. 2

Fig. 1 is a side elevational view of an electrode wheel holder showing my design; and

Fig. 2 is a front elevational view thereof.

The opposite side and the rear, not shown, have substantially the same appearances, respectively, as the side and front shown in Figs. 1 and 2.

I claim:

The ornamental design for an electrode wheel holder, as shown and described.
